UNITED STATES PATENT OFFICE.

ALVIN S. HAINES, OF SLATINGTON, PENNSYLVANIA.

MAIL-BAG.

SPECIFICATION forming part of Letters Patent No. 323,670, dated August 4, 1885.

Application filed May 19, 1885. (No model.)

To all whom it may concern:

Be it known that I, ALVIN S. HAINES, a citizen of the United States, residing at Slatington, in the county of Lehigh and State of Pennsylvania, have invented certain new and useful Improvements in Mail-Bags, of which the following is a specification, reference being had therein to the accompanying drawings.

10 This invention relates to a mail-bag the mouth of which is fastened by means of a series of staples and a sliding strap provided with a series of tongues which engage the staples.

15 A fastening of this class has heretofore been made in which the sliding strap is composed of a series of centrally-slotted metallic plates hinged together and provided with tongues extending into the slots of the plate. The objections to such a strap are that it is complicated and expensive in construction, and that when one link or plate gives out the entire strap is useless. Hinged metallic pronged links have also been employed as a fastening device 25 in connection with staples; but such a device is expensive, complicated, and cumbersome.

20 A mail-bag of this class has also been made in which the sliding strap is composed of leather and provided with a series of slots 30 along its length, metallic plates having central tongues being attached to said strap opposite said slots. The objections to this construction are that it is expensive to make, and, further, that the slots in the leather strap 35 greatly weaken it, and breakage thereof at one of the tongued plates destroys its utility.

35 The object of this invention is to provide a mail-bag with a fastening of this character which is simple and economical in construction and durable in use, and which can be automatically and instantaneously closed and locked.

40 In the drawings hereto annexed, Figure 1 is a front elevation of this improved mail-bag with the central portion of the body broken out and a portion of the lock-face broken away. Fig. 2 is a transverse section through the bag on the line 2 2 of Fig. 1. Fig. 3 is a vertical section through the lock on the line 3 3 of Fig. 50 1. Fig. 4 is a detail of the sliding fastening strap complete.

Similar letters of reference indicate corre-

sponding parts throughout the several figures of the drawings.

A represents the body of a mail bag or pouch, preferably composed of leather, in any suitable size and shape.

B is the flap thereof, which may be an extension of the material composing one side of the body, or another piece suitably secured thereto. This flap is adapted to fold over the upper edge of the bag and close the mouth thereof in a manner well understood, and it is secured in closed position by means of the devices hereinafter described.

65 That side of the bag to which the flap is attached, and which I term the "back," carries a number of staples, D, secured thereto by rivets or otherwise. In the opposite side or "face" is a series of holes, through which these staples extend when the mouth of the bag is closed. The flap B is of two thicknesses, forming a pocket, both thicknesses being provided with a series of holes registering with those in the face. The staples D are 75 thus permitted to pass through the face and flap.

60 Within the aforesaid pocket of the flap B, between the two thicknesses composing the same, slides a fastening-strap, C. This strap 80 C is composed of leather or other suitable flexible material, and is provided with a series of recessed bolts, D, which project laterally from the strap. These bolts are stamped out from sheet metal, and consist of an attaching-plate, a, a shank, b, and a tongue, c, projecting laterally from the shank parallel with the strap, the end of the tongue being rounded, as shown in Fig. 4. These sheet-metal bolts 85 are riveted to the leather strap by means of rivets, which pass through the attaching-plate thereof and through the strap. The inner edges of the recesses in the bolts forming the tongues thereon are flush with the lower edge of the leather strap, and the leather rests 90 against the staples and serves as a guide in the sliding of the strap. As thus constructed the strap is integral and solid throughout, except the small perforations for the rivets, and consequently is strong and durable.

10 In case one or more of the bolts gets broken it can be readily replaced by another of similar construction. The shape of the bolts is such that they can be arranged close together

on the strap, so that a comparatively large number of locking staples and bolts can be used in a single bag, thus increasing the security of the pouch. One end of the strap 5 projects through a hole in one end of the pocket of the flap, and is provided with a ring, E, which serves as a handle for sliding the strap to release the bolts from the staples and unfasten the bag. This strap is provided near 10 its inner end with an angular link, F, fixed thereto. This link is attached edgewise to said strap by means of screws or otherwise, and projects through a slot, d, in the face of the pocket, being provided at its outer end with 15 a number of slots, e.

Attached to the flap B of the bag, at one corner thereof, is a lock, G, within the casing of which are pivoted several hook-shaped tumblers f, separated by intermediate plates, 20 g, which are provided with angular recesses at the inner lower corner of the case. The outer plate of the case and the intermediate plates between the tumblers are provided with registering key-holes i, and the tumblers 25 are provided opposite said key-holes with notches n of the same or different depths; and a key, H, provided with a series of lugs of the same or different lengths, is adapted to actuate all of said tumblers simultaneously. The link 30 F, attached to the fastening-strap, is beveled at its outer end and adapted to enter a slot in the inner end of the lock-case. The pivoted tumblers ride over said link, and their hooked ends take into the slots e therein. 35 Band-springs h tend to throw down the hooked ends of the tumblers.

The operation is as follows: The bag being opened and the fastening-strap drawn out as far as the length of the slot d will permit, the 40 flap B is closed over the top of the front side of the bag, the staples passing through the vertical slots in the flap. Pressure is then applied to the link F, attached to said strap, until the latter is moved toward the left a 45 distance sufficient to cause the end of said link to enter the lock and be grasped by the tumblers therein. During this movement the tongues c of the bolts D, attached to the strap within the pocket of the flap, enter the staples 50 and fasten the bag. When the bag is to be opened, the key is inserted in the lock and

turned through half a revolution, whereby the tumblers of the lock are lifted out of contact with the slotted link on the fastening-strap. The strap is then drawn toward the right by 55 pulling upon the ring E. By this movement the tongues are withdrawn from the staples and the flap is free to be opened.

I claim as my invention—

1. The combination, in a mail-bag, of a series 60 of staples, a pocket-flap provided with a series of vertical slots for the staples, and with a horizontal slot in its outer face, a lock attached to said pocket-flap and projecting through one end thereof, a sliding strap within said pocket-flap, a series of angular sheet-metal bolts projecting laterally from said strap for engaging the staples, and an angular link attached to said strap through the horizontal slot of the pocket-flap, the outer end of said link being 65 adapted to enter the lock, substantially as described.

2. A fastening-strap for mail-bags, consisting of a solid strap of leather provided with sheet-metal bolts rigidly secured thereto, said 70 bolts projecting laterally beyond the edge of the strap and having tongues parallel therewith, substantially as described.

3. A fastening-strap for mail-bags, consisting of a solid strap of leather provided with 80 sheet-metal bolts rigidly secured thereto, said bolts projecting laterally beyond the edge of the strap and having recesses whose inner edges are even with said edge, the lateral projections being provided with tongues parallel 85 with said strap, substantially as described.

4. In a mail - bag the combination of a pocket-flap provided with a longitudinal slot for the locking-link, and with vertical slots for the staples, a sliding strap within said flap 90 provided with a series of locking-bolts, a link attached to said strap through said horizontal slot of the pocket-flap, provided with a series of slots at its outer end, and a lock attached to said flap, provided with a series of spring- 95 actuated tumblers for engaging the slots of said link, substantially as described.

ALVIN S. HAINES.
